INVENTOR.
JAMES ANDERSON

ATTORNEYS

UNITED STATES PATENT OFFICE.

JAMES ANDERSON, OF NICOLAUS, CALIFORNIA.

POWER APPARATUS.

Application filed August 24, 1921. Serial No. 495,012.

To all whom it may concern:

Be it known that I, JAMES ANDERSON, a citizen of the United States, and resident of Nicolaus, county of Sutter, and State of California, have invented a new and useful Power Apparatus, of which the following is a specification.

The present invention relates to improvements in pumps and is a combination of a siphon and a centrifugal pump. Its object is to provide a pump that can normally be used as a siphon but can be very easily changed into a centrifugal pump when the level of the water to be drawn on gets so low that the siphon would not work. My pump is intended mainly for irrigation purposes and in perfecting it I had in view land that is separated from a river by a levee and where the water at certain times of the year rises above the level of the land so that it can be turned on the land by an application of the principles of gravity through the medium of a siphon, but where at other times the water level is below the land level so that power is required to pump it on the land. Under these conditions the farmer very often does not feel justified in going to the expense of installing an extra pumping plant in addition to his siphon, but would probably find it convenient to use my combination siphon and pump.

While my invention has thus been developed in view of certain conditions I do not wish to be understood as confining myself thereby, but I wish to get protection on the principles involved as defined in the claim without being limited by the particular embodiment of the same shown in the drawings and the description.

In the accompanying drawing Figure 1 shows a plan view of my combined siphon and centrifugal pump, Figure 2 a side view of the same, Figure 3 a side view of the same, partly in section, with certain parts shown turned on the axis of the body of the pump, Figure 4 an end view of a propeller used in my pump, Figure 5 a sectional view through the same along line 5—5 of Figure 4, Figure 6 a detail end view of a standard supporting the pump and Figure 7 a cross-section through one of the blades of the propeller along line 7—7 of Figure 4.

Referring to the drawings in detail, it

will be seen that my combined siphon and pump (1), which is represented in the drawing as standing on the top of a levee (2), rests on the boards (3) and is supported by the standard (4), which is shown in end view in Figure 6 and comprises a strut (6) and a tubular ring (7) carried by the same. The latter consists of two halves which are adapted to be secured together by bolts (8) penetrating holes (9) in registering flanges (11) of the two halves. This ring embraces the body of my pump (12) and is provided with an annular recess (14) adapted to receive an annular projection (16) on the outside of the pump so that the pump can be rotatably adjusted in the ring but does not slide in the same.

The pump (12) forms a part of a siphon, which latter comprises a suction pipe (18), a horizontal pipe adapted to carry the water through a desired distance, and the discharge pipe (21). My pump forms a portion of the horizontal pipe and consists of a tubular body (22) having a diameter about twice the length of the siphon diameter. To connect it into the pipe, a portion of the horizontal pipe is removed and the remaining portions are axially disaligned, so that one of said portions (23) may be axially aligned with the pump, while the other portion (24) may be connected to the body of the pump by a slanting pipe (25) entering the side of the body. This latter is conically reduced at its front end to be connected to pipe (23) by means of the two flanges (26) and (27). The rear end of this pump (12) may be closed by an ordinary plate, not shown in the drawing, secured to the flange (28) of the body, and in that case the pump is inactive and the whole apparatus used as a siphon only.

To use the pump I take off the ordinary plate and use in its place the plate (31) shown in the drawing. It is secured to the flange (28) by means of bolts (29) and has a nozzle shaped projection extending into the inside of the pump adapted to serve as a bearing for the shaft (32) which extends through said projection and carries, at its end, the propeller (33). The latter consists of the hub (34), a plurality of blades (36) and a rim (37) which latter comes rather close to the periphery of the

tubular body of the pump and bears against an annular ring (38) secured to the inside of the pump body in front of the propeller to keep water from passing in a rearward direction between the rim and the body. The propeller blades are shaped as shown in Figure 7, that is the suction side (39) has a steeper pitch than the discharge side, whereby strong suction and high pressure are obtained.

Near the propeller a brass bushing (41) is provided in the bearing for the shaft, and where the shaft (32) enters the face plate, packing (42) is introduced in an annular recess (43) and pressed inwardly by the gland (44) actuated by a cap (46) secured to the face plate by means of bolts (47). In this manner an absolutely water and air tight fit is obtained around the shaft (32).

The far end of the shaft (32) rests in the bearing (51) supported on the standard (52). This bearing is shown in section in Figure 1 and comprises a bearing container (55) to which a cap (53) is screwed. A bolt (54), having a head (56) outside the cap and a disc (52) secured to its inner end, extends through the cap and is adapted to be adjusted in the same by being screwed backward and forward. The disc serves as the outer race of a thrust ball bearing, the inner race being formed by a sleeve secured on the reduced end of the shaft (32). A bushing (59) separates the shaft from the bearing container which latter is provided with inner annular grooves (61) for the reception and distribution of oil. The pump is run by any power available, which may transmit motion to the shaft by means of the pulley (62).

To prime the pump I use an ordinary hand pump (63) as shown in Figure 2, by means of which the air may be pumped out of the body of the pump, after the discharge pipe has been air tightly closed.

A removable plate (64) allows the pump to be cleaned by hand in case the passages

have become obstructed by the accumulation of weeds, etc.

The operation of the mechanism will be readily understood. When the level of the water to be pumped is higher than the land, the siphon alone is used. When the water recedes during the dry season, so that its level falls below the level of the land, the pumping mechanism can be easily installed and the water pumped on the land. My mechanism can at the same time readily be used to pump in the opposite direction by merely reversing the rotation of the shaft. This may become of extreme importance in case of heavy rainfalls or floods, where it is desired to pump the water from the land so as to keep the crops from being drowned. The fact that the body of my pump is rotatable in its bearing further enables the operator to easily turn the discharge pipe upward so as to lead the water into a tank or the like, as shown in Figure 3.

Proper valves (65) and (66) are provided in the suction and discharge pipes to regulate the amount of liquid to be handled by the pump.

I claim:

In combination, a levee siphon pipe, said pipe having in its most elevated portion an enlarged section joined through one end and one side to the line of pipe leaving one end only of the section free, an annular abutment within the section, a screw pump runner within the section between the free end and the abutment, said runner having a peripheral ring adjacent the abutment and being supported on a power shaft projecting through the free end, a closure plate detachably secured to the free end carrying a supporting bearing for the shaft, a bearing spaced beyond the free end supporting the extreme end of the shaft, and means on the latter bearing for adjusting the shaft axially for determining the clearance of the abutment and ring.

JAMES ANDERSON.
